UNITED STATES PATENT OFFICE.

VALTIN F. BOEHM, OF CHICAGO, ILLINOIS.

PROPELLER.

1,359,150.

Specification of Letters Patent. Patented Nov. 16, 1920.

Application filed August 4, 1919. Serial No. 315,120.

To all whom it may concern:

Be it known that I, VALTIN F. BOEHM, a citizen of the United States, residing at Chicago, in the county of Cook and State 5 of Illinois, have invented a certain new and useful Improvement in Propellers, of which the following is a full, clear, concise, and exact description, reference being had to the accompanying drawings, forming a 10 part of this specification.

The invention relates to propelling devices and particularly to these devices designed for propelling motor boats, aeroplanes and other similar motor driven vehicles.

The invention has among its various objects the production of an arrangement whereby water or air craft and other above referred to vehicles may be propelled at an 20 increased speed without demanding a relatively greater engine speed.

It is an object of the invention to produce a structure for accomplishing this end, which is simple, and demands only 25 few parts most of which may be bought in the open market.

The invention will be explained in connection with a motor boat, and in conjunction with the accompanying drawings 30 which show same applied thereto, and in which—

Figure 1 is a top plan view of the stern of a launch and having invention applied thereto, and

Fig. 2 is a sectional view taken on line 2—2 of Fig. 1 looking in the directions of the arrows.

Generally speaking the invention contemplates the use of one or more shafts 40 having a propeller provided thereon which have both a rotary and a reciprocal motion, to cause the craft to be propelled. When the structure employs two shafts, these will preferably be reciprocated alternately, and be arranged upon opposite sides of the reciprocating means.

The mechanism for accomplishing this rotary and reciprocal motion, includes the motor shaft 10 which is supported by the 50 bearing brackets 11—11 and has secured to it the gear 12 and the rotatable element 13 having a cam groove 14 provided therein, and which provides the means for reciprocating said shafts.

The gear 12 meshes with gears 15 and 16 55 which are arranged upon the reciprocating

shafts 17 and 18 respectively, they being keyed or otherwise secured to these shafts so as to cause them to reciprocate therewith.

These shafts are supported in bearings 20—20 and are provided with the stuffing boxes 21 to prevent leakage between the hull of the boat and the shaft, and have the propeller 22 provided upon their extremities. These propellers may be of the usual solid type or may be designed so that the blades thereof may be manipulated to cause a reversal of the direction of movement of the launch, without reversing 70 the engine. Each of the shafts 17 and 18 have secured thereto a block 23 having the roller 24 which extends inwardly and into the cam groove 14 of the rotatable element 13. These blocks 23 each have an extension 25 extending outwardly therefrom and carry the squared slide blocks 26 which are arranged in the stationary member 27, the upper ends of which are grooved to receive them and permit said blocks to move 75 with relation thereto when reciprocated by the rotatable element 13.

The members 27 prevent the blocks 23 from turning with the shaft, and said blocks are held in their proper relative positions upon said shafts by the collars 28—28 which are arranged upon the opposite sides of said blocks and are permanently fastened to the shafts.

It will thus be seen that upon the rotation of the motor shaft 10 that both of the shafts 17 and 18 will be rotated through the medium of the gears 15 and 16 which mesh with the gear 12, provided upon the shaft 10 and by virtue of the fact that the 90 rotatable element 13 is keyed to this shaft, this element will rotate with the shaft, which through the medium of the cam slot 14 and the connection between it and the shafts 17 and 18 will cause a rotating alternating and reciprocating motion to be imparted to the respective shafts.

It is understood that the inward motion of the propeller will not impair or interfere with the forward motion of the boat, 105 as the inclination of the blades will cause the shaft to move inwardly, therefore only upon an outward movement of these shafts is it necessary that any force to drive them longitudinally be applied.

From the foregoing explanation of the construction and operation of the device,

it is evident that the shafts will each have imparted to them a rotating and reciprocating motion which will propel the boat forwardly, also that when two shafts are utilized that a mechanism is provided which will alternately reciprocate said shafts, which will cause the boat to be propelled more smoothly.

Having thus described one embodiment 10 of the invention it is evident that changes and modifications may be resorted to without departing from the spirit of the appended claims.

What I claim and desire to cover by Letters Patent is:—

1. In a device of the class described the combination of a drive shaft, a pair of shafts each having a propeller provided thereon, said shafts being arranged to be rotated and reciprocated relatively to the drive shaft said drive shaft having a single rotatable member provided thereon for reciprocating both of said propeller shafts.

2. In a device of the class described the combination of a drive shaft, a pair of shafts each having a propeller provided thereon said shafts being arranged to be rotated and reciprocated relatively to the drive shaft, said drive shaft comprising a rotatable member having a cam for alternately reciprocating said propeller shafts.

3. In a device of the class described the

combination of a drive shaft a pair of shafts each having a propeller provided thereon, said propeller shafts being arranged to be rotated and reciprocated relatively to the drive shaft, means provided upon the drive shaft for rotating said propeller shafts and having a single rotatable element for alternately reciprocating both of said propeller shafts.

4. In a device of the class described the combination of a propeller shaft and a drive shaft arranged parallel to the propeller shaft, said drive shaft having a cam for reciprocating the propeller shaft and means for rotating said propeller shaft.

5. In a device of the class described the combination of a drive shaft and a pair of propeller shafts each of which have a propeller provided thereon said propeller shafts being arranged parallel with the drive shaft, and means provided upon the drive shaft for rotating and alternately reciprocating the propeller shafts.

6. In a device of the class described the combination of a shaft having a propeller mounted thereon, a drive shaft and means arranged upon the drive shaft for rotating and reciprocating said propeller shaft.

In witness whereof I hereunto subscribe my name this 1st day of July, A. D. 1919.

VALTIN F. BOEHM.
